S. PETERS.

CONDIMENT HOLDER.

APPLICATION FILED JAN. 23, 1919.

1,375,929.

Patented Apr. 26, 1921.

UNITED STATES PATENT OFFICE.

SHAFEH PETERS, OF PARIS, TEXAS, ASSIGNOR OF ONE-HALF TO CONSTANTINE M. HADDAD, OF TYLER, TEXAS.

CONDIMENT-HOLDER.

1,375,929.

Specification of Letters Patent. Patented Apr. 26, 1921.

Application filed January 23, 1919. Serial No. 272,754.

To all whom it may concern:

Be it known that I, SHAFEH PETERS, a citizen of the United States, residing at Paris, in the county of Lamar and State of Texas, have invented certain new and useful Improvements in Condiment-Holders; and I do hereby declare the following to be a full, clear, and exact description of the invention, such as will enable other skilled in the art 10 to which it appertains to make and use the same.

This invention relates to improvements in condiment holders of the character to contain different kinds of ingredients and has 15 for one of its objects the provision of means for controlling the dispensing of said ingredients so that one or the other can be dispensed separately or both simultaneously.

Another object of this invention is the 20 provision of auxiliary chambers closed by the usual perforated top or cover and having a controlling slide adapted to be operated from the exterior of the device so that the ingredients can be controlled into 25 the chambers and outwardly through the cover or top.

A further object of this invention is the 30 provision of a condiment holder of the above stated character, which shall be simple, durable, and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and claimed.

40 For a complete understanding of my invention, reference is to be had to the following description and accompanying drawing, in which:

Figure 1 is a side elevation of a condiment 45 holder constructed in accordance with my invention,

Fig. 2 is a vertical sectional view of the same,

Fig. 3 is a sectional view taken on the line 50 3—3 of Fig. 2 looking in the direction indicated by the arrow, and

Fig. 4 is a plan view of the device with the cover or top removed.

Referring in detail to the drawing, the 55 numeral 1 indicates a body of a condiment

holder having the usual tapering side walls and the flat bottom wall 2 on which the device is adapted to rest. The body 1 is divided by a partition 3 forming chambers 4 and 5 which are adapted to contain salt and pepper, respectively. The upper edge of the partition 3 terminates in a plane with the upper edge of the side walls of the wall 1. A horizontal partition 6 is formed upon the partition 3 and side walls of the body 1 to 60 form auxiliary chambers 7 and 8, to the salt and pepper chambers 4 and 5, respectively. The partition 6 is provided with circular openings 9 permitting a communication from the auxiliary chambers to the salt 65 and pepper chambers 4 and 5. At a point above the partition 6, the partition 3 is provided with a slot 10 in which is positioned a pivot pin 11. The pivot pin 11 pivotally supports a controlling slide or member 12 70 that has formed thereon an extension 13 that extends through a slot in the side wall of the body at a point above the partition 6. The extension 13 has formed thereon a suitable handle 14 so that the slide or controlling 75 member 12 can be swung to close either of the openings 9 thus preventing the ingredients of the corresponding chambers 4 or 5 from passing into the corresponding auxiliary chambers, thus permitting the ingredients to be dispensed from the main, or 80 salt and pepper chambers separately into the auxiliary chambers. If desired, the slide or controlling member 12 can be so positioned as to leave both of the openings 9 of 85 the partition 6 uncovered, so that the ingredients within the chambers 4 and 5 can be simultaneously dispensed into the auxiliary chambers 7 and 8 by turning the device up-side-down.

90 95
Screw threads are formed upon the upper edge of the side walls of the body 1 to cooperate with screw threads formed upon an annular flange 15 of a perforated cover 16, which overlies the auxiliary chambers 7 and 8 and permit the escape of the ingredients from the auxiliary chambers when the device is inverted.

When it is desired to fill the chambers 4 and 5 with salt and pepper, the cover 16 is 100 105 removed and the slide or controlling member 12 is so positioned as to leave the openings 9 uncovered and the salt and pepper then may be poured into their respective chambers.

While I have shown and described the preferred embodiment of my invention, it will be understood that minor changes in construction, combination, and arrangement of parts may be made without departing from the spirit and scope of the invention as claimed.

Having thus described my invention, what I claim is:—

10. A condiment holder comprising a body having its upper end open and screw threaded, a partition formed in said body to provide a pair of main compartments and said partition terminating in a plane with
15. the upper edge of said body, horizontal partitions formed on the first named partition and wall of said body to provide auxiliary compartments and said horizontal partitions having openings to communicate the main

and auxiliary compartments, a perforated 20 cover threaded to the upper end of said body and bearing against the upper end of the first named partition, said first named partition and body each having a slot above the horizontal partitions, and a closure element 25 pivoted in the slot of the first named partition and extending through the slot of the body so that the same can be moved from one auxiliary compartment to the other for closing and opening the openings between 30 the main and auxiliary compartments.

In testimony whereof I affix my signature in presence of two witnesses.

SHAFEEH PETERS.
